NEEDLE-CONTROLLING TRANSFER MEANS FOR KNITTING-MACHINES.

1,084,778.

Specification of Letters Patent.

Patented Jan. 20, 1914.

Application filed June 30, 1911. Serial No. 636,302.

To all whom it may concern:

Be it known that I, JOSEPH H. ZENS, a citizen of the United States, and a resident of Milwaukee, in the county of Milwaukee 5 and State of Wisconsin, have invented an Improvement in Needle-Controlling Transfer Means for Knitting-Machines, of which the following description, in connection with the accompanying drawings, is a specification, like characters on the drawings representing like parts.

This invention relates to needle controlling transfer means for knitting machines, particularly of the circular type.

15 In order that the principle of the invention may be readily understood, I have disclosed a single embodiment thereof in the accompanying drawings, wherein—

Figure 1 is a central vertical section of a 20 circular knitting machine and showing inside elevation, my invention applied thereto; Figs. 2, 3 and 4 are central vertical sections of the upper portion only of the needle and cam cylinders of a circular knitting machine; 25 showing successive positions assumed by the needle cylinder and needles in transferring a rib top thereto; Fig. 5 is a view taken at right angles to Fig. 1 of the mechanism for raising and lowering the needle cylinder; and Fig. 6 is a view in side elevation of the 30 needle cylinder elevating and lowering mechanism taken at 180 degrees from the position shown in Fig. 1. Fig. 7 is a detail of the elevating mechanism.

35 This invention particularly relates to means for changing the relative heights of the needle and cam cylinders of a circular knitting machine in the transfer of a rib top from the transfer ring to the knitting needles. While I have herein represented the needle cylinder as adjustable for the purpose stated, it is evident that the described relative adjustment may be effected by raising and lowering the cam cylinder.

40 The terms "needle cylinder" and "cam cylinder" are throughout used in a generic sense, as it is evident that my invention may be applied to other types of knitting machines wherein needle and cam carriers of 45 a straight or other form are employed. The invention is, however, peculiarly adapted to circular knitting machines, and especially to those having latch needles independently reciprocal in the knitting operation. Obviously the invention may be employed in

knitting machines wherein either the needle cylinder or the cam cylinder is rotated or reciprocated in the knitting operation, and it may be used in conjunction with means acting automatically or otherwise to change 60 the height of the needle or cam cylinders, thereby to effect change in the length of the stitches.

Referring more particularly to the drawings, I have therein represented in Fig. 1 a portion of a circular knitting machine of the general type shown in the patent to George D. Mayo, No. 726,178, it being evident, however, that the invention is applicable to any other type of machine as previously stated. In said figure, the needle cylinder is indicated at 1 and the cam cylinder at 2, these being of any suitable type not herein necessary to describe. Carried by the needle cylinder are needles 3, here shown as of the independent latch type. Supported upon the needle cylinder is a web-holder ring 4 having web-holders 5 actuated by a web-holder cam ring 6 in the usual manner. Supported upon the cam ring is a latch or yarn ring 7 having a yarn guide 8. The said ring 7 is pivoted at 9 upon the cam ring, so that it may be swung upwardly therefrom to permit the application of the transfer ring, as will be readily understood. A portion of the narrowing and widening mechanism is indicated at 10, this being of a type often shown in machines built under said Mayo patent. The parts thus far described may be of any suitable or ordinary construction and are represented merely for the purposes of illustration.

The needle cylinder 1 is provided with a downward prolongation 11 having a socket 95 whereto is attached a post or supporting rod 12 similar to that shown in said patent and supported at its lower end upon the bed 13 of the machine, where it engages the upper end of an adjusting screw 14 to 100 permit the correct positioning of said rod in assembling the machine. Surrounding the said rod or post 12 and resting at its lower end upon a suitable collar 15, is a sleeve 16 having formed with or secured there- 105 to a handle 17, by which said sleeve may be turned in a suitable arc upon said rod 12. Bolted to the said rod is a split collar 17' having thereon a lug 18 shown most clearly in Fig. 7 as engaged by a cam 19 formed 110

upon the upper edge of said sleeve 16. As the sleeve 16 is turned in a clockwise direction, viewing Fig. 7, the cam 19 rides under the lug 18, thereby elevating the post or rod 12 and the needle cylinder 1 with its needles, so as to bring them to the desired positions in effecting transfer of the rib top to the needles. Movement of the lever 17 in the opposite direction restores the needle cylinder and rod 12 to its former position. If desired, I may in conjunction with the said mechanism, provide means for automatically changing the length of the stitches during the knitting operation. For this purpose, I have in Fig. 1, shown a cam drum 20 adapted to coöperate with the lever 21 in a usual manner to elevate the needle cylinder at the desired times. For this purpose, the collar 17' is provided with an adjusting screw 22 adapted to engage with the upper face of said lever 21, thereby to support the rod 12 and the needle cylinder in the desired position.

Heretofore, so far as I am aware, it has been customary to elevate the needle cylinder to a position at which the transfer ring with its ribbed top has been applied to the needles, after which the stitches are drawn onto the needles, the transfer ring is removed therefrom and the needle cylinder is lowered to knitting position. In such operation the loops of the rib top have very frequently been drawn so far down upon the needles or certain of them that the loops have come under the latches of the needles instead of merely under their hooks. The result has been that when the latches are first closed in the knitting operation, such needles drop their stitches.

An important feature of my invention involves the provision of means, preferably automatic, whereby the needle cylinder, after having been elevated for the reception of the transfer ring and then having been lowered to an intermediate position, preferably the tuck position, for the transfer of the loops to the knitting needles, is then lowered to the knitting position. In the said intermediate or tuck position the latches of the needles are so protected that the stitches of the rib top cannot be drawn below the latches in the transfer operation, but merely under the hooks. As above stated, preferably the lowering of the needle cylinder from tuck position to knitting position is effected automatically, so that carelessness of the operative in failing to restore the needle cylinder to knitting position cannot result in the dropping of stitches.

In Fig. 2, I have represented the needle cylinder as elevated for the reception of the transfer ring, which is placed upon the web-holders in the usual manner. In order to position the needle cylinder at this point, the lever 17 is turned in a clockwise direction as

far as possible, so as to elevate the rod 20 to its full height. In this position, all the needles are practically level with the sinker ring. Thereupon in accordance with my invention, the needle cylinder is dropped sufficiently to effect the passing of the needles through the stitches of the rib top upon the transfer points of the transfer ring. In order that upon the return movement of the lever 17 the cylinder and needles may be brought to an intermediate position and thereafter be lowered to the full knitting position in a preferably automatic manner, I have provided means adapted in this embodiment of my invention, to be interposed between the upper face of the lever 21 and the set screw 22 upon the collar 17' carried by the rod 12. The precise point at which the needle cylinder is supported in the intermediate position depends upon the proportioning of the parts and may be varied within the scope of my invention. Preferably, however, I support the needle cylinder at the tuck position as shown most clearly in Fig. 3, wherein the outer ends of the latches 23 of the needles are represented as below the web-holders, so as to prevent the stitches when transferred to the needles from being drawn below the points of the latches as previously stated. An additional and very important advantage in positioning the needle cylinder at the intermediate or tuck position flows from the fact that operatives, when transferring the web to the needles, frequently fail, through carelessness, to secure the transfer of all the loops to the needles. After the transfer ring has been removed from the needles, it is the common practice for the operative, when the needles are in their projected position, to pick up the loops that have not been properly transferred and to place them upon the needles. In doing this, there is very great liability that the loops will be pulled from the adjacent needles because such loops have come under the latches of the needles instead of merely under their hooks, as previously described. When, however, the loops are transferred in accordance with my invention, as previously described, it is substantially impossible, when the operative picks up drop stitches, to pull off stitches from adjacent needles. While to effect the desired result, I may employ any suitable means, I have herein represented a split collar 24 bolted upon the rod 12 and having pivoted thereon at 25 a latch or lever 26 having a toe 27 adapted to be interposed as described between the adjusting screw 22 and the lever 21. The weight of the latch 26 is such that it tends to ride under the adjusting screw 22, so that as the handle or lever 17 is returned in a counter-clockwise direction to its original position, the needle cylinder is dropped, not to the knitting position, but to an intermediate

or tuck position, at which position the transfer of the stitches to the needles is effected.

After the stitches have been transferred as described, the latch or yarn ring 7 is then 5 swung downward into the position indicated in dotted lines in Fig. 3, in which position the latches 23 of the needles are protected as shown and are prevented from flying upward or closing, thus permitting the dropping 10 of stitches, which would have resulted had the stitches been placed below the latches of the needles. In order that the needle cylinder may now be lowered to knitting position, and in a preferably automatic 15 manner, I have provided suitable means to engage the latch 26 and withdraw its toe 27 from its interposed position. For that purpose, I have provided the said latch with an arm 28 adapted to be struck by a suitable 20 lug or projection active upon the commencement of relative rotation of the needle and cam cylinders. For that purpose I have herein represented a lug 29 carried by or formed with a split collar 30 mounted upon 25 the main drive shaft 31 of the machine, or if desired upon the hub of the gear 32 meshing with the gear upon the ring of the cam cylinder.

The position of the parts is such that substantially 30 immediately upon the commencement of rotation of the cam cylinder 2 the lug 31 moving in a clockwise direction, viewing Fig. 6, engages the arm 28, thereby withdrawing the toe 27 of the lever 26 from its interposed position referred to and permitting the automatic lowering of the needle cylinder into its knitting position; that is, into the position shown in Fig. 4.

It is apparent from the foregoing description that I have provided simple yet efficient means which may readily be attached to standard parts of a knitting machine at slight expense to secure the transfer of stitches from a rib top or other web to the 45 knitting needles without dropping of stitches. It is evident that the automatic lowering of the needle cylinder from the stitch transfer position to the knitting position will prevent all dropping of stitches 50 even though the operative should neglect to lower the cylinder after the transfer of stitches to the needles.

Having thus described one illustrative embodiment of my invention, I desire it to be understood that although specific terms are employed, they are used in a generic and descriptive sense and not for purposes of limitation, the scope of the invention being set forth in the following claims.

60 Claims.

1. Knitting mechanism comprising in combination needle and cam cylinders, means to impart relative rotation to the said cylinders, means to position the needle cylinder at 65 the tuck point to permit the transfer of the

stitches to the knitting needles, and means acting automatically upon commencement of relative rotation of the needle and cam cylinders to effect the lowering of the needle cylinder to knitting position.

2. Knitting mechanism comprising in combination needle and cam cylinders, means to position the needle cylinder for the reception of a transfer device, means to lower the needle cylinder to stitch transfer position, and means additionally to lower said cylinder to knitting position.

3. Knitting mechanism comprising in combination needle and cam cylinders, means to position the needle cylinder for the reception of a transfer device, means to lower the needle cylinder to stitch transfer position, and automatically acting means to effect the lowering of said cylinder to knitting position.

4. Knitting mechanism comprising in combination needle and cam cylinders, means to position the needle cylinder for the reception of a transfer device, means to lower the needle cylinder to stitch transfer position, and means acting automatically upon commencement of relative rotation of the needle and cam cylinders and prior to the knitting operation, to effect the lowering of the needle cylinder to knitting position.

5. Knitting mechanism comprising in combination needle and cam cylinders, a main drive shaft for imparting relative rotation to said cylinders, means to position the needle cylinder for the reception of a transfer device, means to lower the needle cylinder to stitch transfer position, and means actuated by said main drive shaft to effect the lowering of the needle cylinder to knitting position prior to the commencement of the knitting operation.

6. Knitting mechanism comprising in combination needle and cam cylinders, means to raise the needle cylinder for the reception of a transfer device, means to lower the needle cylinder to tuck position for the transfer of the stitches to the knitting needles, and means active upon the commencement of relative rotation of the needle and cam cylinders, to effect the lowering of the needle cylinder to knitting position.

7. Knitting mechanism comprising in combination needle and cam cylinders, the former having a downward prolongation for effecting the raising and lowering thereof, manual means active upon said prolongation for raising said needle cylinder for the reception of a transfer device and for lowering the same to tuck position for the transfer of the stitches to the knitting needles, and means automatically active to effect the lowering thereof to knitting position at the commencement of the knitting operation.

8. Knitting mechanism comprising in combination needle and cam cylinders, the

- 4 former having a downward prolongation for effecting the raising and lowering thereof, manual means active upon said prolongation for raising and lowering the needle cylinder, 5 means to arrest the lowering of said cylinder at tuck position for the transfer of stitches to the knitting needles, and means active at the commencement of the knitting operation, to permit the descent of the needle cylinder 10 to knitting position.
9. Knitting mechanism comprising in combination needle and cam cylinders, latch needles therefor, a web-holder ring and web-holders, means to elevate the needle cylinder 15 and needles for the reception of a transfer ring, means to lower the needle cylinder and needles to a position where the points of the needle latches are between the web-holders, for the transfer of the stitches to the needles, 20 and means automatically active upon the commencement of relative rotation of the needle and cam cylinders, to effect the lowering of the needle cylinder to knitting position.
- 25 10. Knitting mechanism comprising in combination needle and cam cylinders, latch needles therefor, a web-holder ring and web-holders, a removable yarn ring, means to elevate the needle cylinder and needles 30 for the reception of a transfer ring, means to lower the needle cylinder and needles to a position where the points of the needle latches are between the web-holders, and means automatically effective just prior to 35 the commencement of the action of the stitch cam upon the needles, to effect the lowering of the needle cylinder to knitting position.
11. Knitting mechanism comprising in combination needle and cam cylinders, the former having a downward prolongation, a main drive shaft to effect relative rotation of said cylinders, manual means to act upon said prolongation, thereby to raise and lower the needle cylinder, a pivoted device carried by said prolongation and adapted to be interposed to arrest the descent of the needle cylinder at tuck position, and a member carried by said drive shaft to displace 45 said pivoted device and permit the descent 50 of the needle cylinder to knitting position.
12. Knitting mechanism comprising in combination needle and cam cylinders, the former having a downward prolongation, a main drive shaft to effect relative rotation 55 of said cylinders, manual means to act upon said prolongation, thereby to raise and lower the needle cylinder, a latch pivoted upon said prolongation and adapted to be interposed between the same and a support there- 60 for to arrest the descent of the needle cylinder at tuck position, and a projection carried by said main drive shaft and active upon said latch at substantially the commencement of rotation of said drive shaft, to 65 remove said latch from its interposed posi-
- tion and permit the descent of the needle cylinder to knitting position.
13. Knitting mechanism comprising in combination needle and cam cylinders, a main drive shaft to impart relative rotation to said cylinders, means to change the relative height of said cylinders, thereby to position the needles at substantially tuck elevation, and means automatically active at the commencement of relative rotation of 70 said cylinders to change the relative height of said cylinders, thereby to position the needles for the knitting operation.
14. A knitting mechanism comprising in combination, needle and cam cylinders, manual means for raising and lowering the needle cylinders, means to arrest the lowering of said cylinder at tuck position for the transfer of stitches to the knitting needles, and means active at the commencement of 75 the knitting operation to permit the descent of the needle cylinder to knitting position.
15. Knitting mechanism comprising in combination needles and cam cylinders, means to impart relative rotation to the said cylinders, means to position the needle cylinder at the tuck point to permit the transfer of the stitches to the knitting needles, and means initiated in action by the commencement of relative rotation of the needle and cam cylinders, thereby to effect the lowering 80 of the needle cylinder to knitting position.
16. Knitting mechanism comprising in combination; needle and cam cylinders, 85 means to position the needle cylinder for the reception of the transfer device, means to lower the needle cylinder to stitch transfer position, and means initiated in action by the commencement of relative rotation 90 of the needle and cam cylinders, thereby to effect the lowering of the needle cylinder to knitting position.
17. Knitting mechanism comprising in combination, needle and cam cylinders, 95 means to position the needle cylinder for the reception of the transfer device, means to lower the needle cylinder to stitch transfer position, and automatically acting means additionally to change the vertical position 100 of the needle cylinder relative to the cam cylinder, thereby to prevent dropping of stitches from the knitting needles in commencing the knitting operation after transfer of stitches from said transfer device to 105 the knitting needles.
18. Knitting mechanism comprising in combination needle and cam cylinders, the former having a downward prolongation for effecting the raising and lowering thereof, manual means active upon said prolongation for raising said needle cylinder for the reception of a transfer device and for lowering the same to tuck position for 110 the transfer of the stitches to the knitting 115 needles.
- 125 19. Knitting mechanism comprising in combination needle and cam cylinders, the former having a downward prolongation for effecting the raising and lowering thereof, manual means active upon said prolongation for raising said needle cylinder for the reception of a transfer device and for lowering the same to tuck position for 120 the transfer of the stitches to the knitting 125 needles.

needles, and means rendered active by initiation of the knitting operation to effect the lowering of the needle cylinder to knitting position.

5 19. Knitting mechanism comprising in combination needle and cam cylinders, the former having a downward prolongation for effecting the raising and lowering thereof, manual means active upon said prolongation for raising said needle cylinder for the reception of a transfer device and for lowering the same to tuck position for the transfer of the stitches to the knitting needles, and means rendered active by initial movement of the main drive shaft to effect the lowering of the needle cylinder to knitting position.

10 20. Knitting mechanism comprising in combination needle and cam cylinders, the

former having a downward prolongation 20 for effecting the raising and lowering thereof, manual means active upon said prolongation for raising said needle cylinder for the reception of a transfer device and for lowering the same to tuck position for the transfer 25 of the stitches to the knitting needles, and rotary means rendered active by initiation of the knitting operation to effect the lowering of the needle cylinder to knitting position.

15 In testimony whereof, I have signed my name to this specification, in the presence of two subscribing witnesses.
